(57) CLAIM

I claim the ornamental design for a golf club shaft, as shown and described.

DESCRIPTION

FIG. 1 is a perspective view of the shaft of one embodiment of the design;

FIG. 2 is a side elevation of one side of the shaft, of the design of FIG. 1;

FIG. 3 is a side elevation of another side of the shaft disposed 90° relative to the view of FIG. 2, of the design of FIG. 1;

FIG. 4 is a side elevation view of the shaft opposite the side shown in FIG. 2, of the design of FIG. 1;

FIG. 5 is a side elevation of the shaft opposite the side shown in FIG. 3, of the design of FIG. 1;

FIG. 6 is a perspective view looking down on the shaft and showing its lower end, of the design of FIG. 1;

FIG. 7 is a perspective view looking up at the shaft and showing its upper end, of the design of FIG. 1;

FIG. 8 is a perspective view of another embodiment of the design, which is identical to the embodiment of FIG. 1, except that light and dark materials are reversed;

FIG. 9 is a side elevation view of one side of the shaft of the design of FIG. 8;

FIG. 10 is a side elevation of another side of the shaft disposed 90° relative to the view of FIG. 9, of the design of FIG. 8;

FIG. 11 is a side elevation view of the shaft opposite the side shown in FIG. 9, of the design of FIG. 8;

FIG. 12 is a side elevation view of the shaft opposite the side shown in FIG. 10, of the design of FIG. 8;

FIG. 13 is perspective view looking down on the shaft and showing its lower end, of the design of FIG. 8; and,

FIG. 14 is a perspective view looking up at the shaft and showing its upper end, of the design of FIG. 8.

Line shading and stippling are used in the drawings to show a contrast between light and dark regions of the design.

The broken line showing is for illustrative purposes only and forms no part of the claimed design.
